UNITED STATES PATENT OFFICE

2,579,951

APPARATUS FOR CASTING HEADS ON PINS

Louis H. Morin, Bronx, and Otto Gries, New Rochelle, N. Y.; said Gries assignor to Crown Fastener Corporation, Warren, R. I., a corporation of Delaware

Application March 12, 1946, Serial No. 653,742

5 Claims. (Cl. 18—30)

1

This invention relates to the formation of die cast heads or enlarged bodies on one end of a pin or rod-like element. More particularly, the invention deals with a novel apparatus for controlling delivery of the pin element or other workpiece from the discharge end of a hopper magazine to casting and trimming stations and in final discharge of the trimmed products from the machine. Still more particularly, the invention deals with an apparatus wherein the pins or other workpieces are supported in the magazine in horizontal position and maintained in such position at the casting and trimming stations, and further wherein in forming the cast head on one pin, the head of a previously formed pin is trimmed, thereby facilitating production of cast heads on pins or similar workpieces at a relatively high rate of speed and consistent with predetermined opening and closing movement of a pair of casting dies employed. The novel features of the invention will be best understood from the following descriptions when taken together with the accompanying drawing in which certain embodiments of the invention are disclosed and in which the separate parts are designated by suitable reference characters in each of the views; and in which:

Fig. 1 is a front face view of a part of a casting machine with part of the construction broken away and in section.

Fig. 2 is a vertical sectional view substantially on the line 2—2 of Fig. 1, with part of the structure shown in elevation, as indicated by the broken lines in Fig. 2 of the drawing.

Fig. 3 is a partial section on the line 3—3 of Fig. 1, omitting parts of the base structure illustrated in Fig. 1.

Fig. 4 is a partial section on the line 4—4 of Fig. 2 on an enlarged scale, showing primarily the workpiece feed and control mechanism in position preparatory to delivering a workpiece to a casting station, with parts of the dies illustrated in the background.

Fig. 5 is a partial section on the line 5—5 of Fig. 4; and

Figs. 6 to 10 inclusive, are diagrammatic views showing successive steps in the method of delivering the workpiece to successive stages in the cycle of operation of the machine.

The present invention deals with casting machines for pressure injecting heated casting material, such as metal alloys or plastics in the cavities or impressions of a pair of relatively movable dies wherein the dies include a pair of trimming tools for trimming castings supported

2

at a trimming station and simultaneously in the operation of forming a next successive casting. Still more particularly, the invention deals with a method of delivering pins or other rod-like elements or workpieces to the casting and trimming stations and in discharge of trimmed castings from the machine and in performing these operations in such manner as to maintain a high rate of production, depending upon the speed of operation of the dies and upon the type and kind of casting material employed.

In Fig. 1 of the drawing is shown a pair of die operating members 15 and 16 upon which a pair of die blocks 17 and 18 are mounted, note 15 Fig. 5, the die blocks having cavities or impressions 19 and 20 with which common gate passages 21 and 22 register and passages 23 and 24 for receiving the shank of pins or other rod-like workpieces 25. The pins or workpieces 25 have heads 26 adapted to be positioned substantially centrally of the cavities or impressions 19 and 20.

Considering now Fig. 2 of the drawing, diagrammatically illustrated at 27 is a goose neck or other unit having a discharge nozzle 28 for discharging heated casting material, such as a metal alloy or a plastic into the cavity or impression of the dies when the latter are in closed position. Below the forming impressions 19 and 20, the dies also have an impression or cavity, as at 29, note Fig. 2, for the reception of the cast head 30, leaving the gate portion 31 protruding to be trimmed off by trimming tools 32, indicated in dotted lines in Fig. 5 of the drawing. The cavity 29 also includes a portion 33 for receiving and supporting the shank of the pins or workpieces 25 adjacent the cast heads 30.

The die operating members 15 and 16 are recessed adjacent inner surfaces of the dies to receive pin guiding plates 34 and 35, and another pair of similar plates 34' and 35' are disposed in spaced relation to outer surfaces of the members 15 and 16, note Figs. 2 and 5 of the drawing.

Between the plates 34 and 34', the member 15 has a projecting pin pick-up and feed finger 36 below which is a table portion 37 extending a greater distance than the finger 36 and spaced from the finger 36 by a large recess 38. The table portion 37 is of a height or thickness corresponding to the spacing between a pin supported at the casting station and a pin supported at the trimming station. The table 37 forms a support for the pin at the casting station, and the lower surface 37' of the table portion clears the upper surface of the pin at the trimming station when the dies are moved into closed position. Below

the table member 37 is a recess 39 which is adapted to receive the projecting table or shelf portion 40 of the member 16, note in this connection Fig. 4 of the drawing. The upper surface of the table portion 37 serves to support the pin in proper position at the casting station. The member 16 is recessed above the table or shelf portion 40, as seen at 41, to receive the table portion 37 when the dies move into closed position.

Suitably supported permanently above the die operating members 15 and 16 is a magazine 42 disposed at the lower end portion of a suitable hopper feed, not shown, and into which magazine pins are dropped for vertical stacking, in the manner partially illustrated in Fig. 4 of the drawing. The magazine comprises a U-shaped frame 43, note Fig. 3, in which is supported two guide plates 44 and 45 by suitable clamps as at 46 and 47. Arranged between the plates 44 and 45 are peripheral or edge spacer strips 48 and 49 for guiding and locating the pins 25, and particularly the heads 26 thereof for aligned delivery with respect to the cavities or impressions 19 and 20 of the dies 17 and 18.

The lower discharge end of the magazine 42 is shown adjacent the upper surface of the die operating members 15 and 16 and the dies 17 and 18 supported therein. The inner edge of the guide strip 48 is curved, as seen at 48', in Fig. 2 of the drawing and the inner surface of the strip 49 is also curved, as seen at 49' in said figure. Between these surfaces and between the surfaces of the plates 44 and 45 are pin guide channels 50 which open through the lower surfaces of the magazine 42 and onto the upper surface 36' of the feed finger 36, note Fig. 4.

The plates 34-34' and the plates 35-35' are secured to the lower portion of the plates 44 and 45, one of which attachments is indicated at the left of Fig. 1, and as further indicated in dotted lines in Fig. 2. The plates 34-34' include at their upper ends shelf extension 51 for supporting the pins 25 in the channel 50. The plates 35-35' have cut out portions 52 spaced above the shelf 51 to form an angular extension 50' to the channel 50, note Fig. 4, which opens into another downwardly extending channel 50'' between adjacent surfaces of each pair of plates 34-35 and 34'-35', the channels 50'' of both pairs of plates being in alinement, as will appear from a consideration of Fig. 5 of the drawing. The channels 50, 50' and 50'' guide and position the pins 25 between the dies and further control final delivery of the cast headed pins from the machine, as shown for example in Fig. 10 of the drawing. In other words, the pairs of plates 34-35 and 34'-35' remain stationary at all times, and are sufficiently spaced to provide a free but controlled passage of the pins downwardly between the dies and the members 15 and 16, whereas the shelves or tables 51, 37 and 40 control vertical positioning of the pins at first the delivery station, second the casting station and thirdly the trimming station.

Considering now Figs. 1 and 2 of the drawings, at 53 is shown a guide strip mounted in a recess 54 of the plate 45 by suitable bolts as at 55. The plate 45 is further recessed, as seen at 56, and in this recess and on the inner surface of the guide strip 53 is a spring pressed catch 57, the spring of which is shown at 58. The catch 57 has a pin 59 operating in a slot 60 in the strip 53. The lower end of the catch 57 has a rounded surface 61, note Fig. 1, adapted to extend into the channel 50' so that when the lowermost pin 25 drops

into the channel 50', the catch 57 will retain the pin against displacement in the channel, whereas the finger 36 can feed the lowermost pin 25 beneath the catch 57 for delivery into the channel 50'', the catch 57 being raised in this operation against the tension of the spring 58.

Considering now Figs. 6 to 10 inclusive, wherein a diagrammatic illustration is shown of the members 15 and 16, in Fig. 6, the position of the parts here diagrammatically illustrated may be regarded as the step of beginning to open the dies after a casting has been formed on the pin 25' with the pin still supported on the table or platform 37 in the channel 50'', and the finger 36 still holding the lowermost pin 25'' in the channel 50.

In Fig. 7, the members 15 and 16 are shown in their fully opened position where the table or shelf 37 has cleared the channel 50'', allowing the pin 25' to drop in the channel 50'' upon the shelf or platform 40 and also allowing the lowermost pin 25'' to drop upon the shelf or platform 51 and in the channel 50', being held in the channel 50' by the spring catch 57.

Considering Fig. 8, in this figure, the dies are shown in a partially closed position, the finger 36 having delivered the pin 25'' in position to drop in the channel 50'' and onto the table or shelf 37 and with the pin 25' still retained upon the shelf or table 40 in the channel 50'.

In Fig. 9, the members 15 and 16 including the dies thereon are in their fully closed position, in which position a cast head is formed on the pin 25'' and the casting of the pin 25' is trimmed by the trimming tools 32.

Now turning to Fig. 10, here the members 15 and 16 are in a partially opened position, the member 16 having been retracted sufficiently to allow the trimmed pin 25' to drop through the lower end of the channel 50'' into a suitable receptacle, not shown, with the table or platform 37 still supporting the pin 25'' at the casting station.

The members 15 and 16 then return to the position in Fig. 6, in which position the member 16 has moved inwardly sufficiently to again have the table or shelf 40 overlap the channel 50'', leaving the pin 25'' still supported at the casting station, similar to the showing of the pin 25' as in Fig. 6. This cycle of operation continues and in each cycle, a trimmed casting is delivered from the machine, a casting is formed on a pin at the casting station and a new pin is delivered at the delivery station. If the members 15 and 16 are actuated toward and from each other, at the rate of three hundred and fifty or more operations per minute, then it will be apparent that three hundred and fifty or more castings will be formed by the machine.

In accordance with the method disclosed, four distinct functions and operations are performed in each cycle of machine operation, namely, delivery, casting, trimming and ejecting. In this method of procedure, three distinct table or supporting platforms are employed at the first three stations, namely for the pick-up and delivery of the pin or workpiece, at the casting station and at the trimming station. All these operations are performed in a simple mechanical and foolproof manner, particularly in the inclusion of the spring catch for retaining the pins against accidental delivery from the lower discharge end of the hopper or from the horizontal channel 50' to the vertical channel 50''.

It will be apparent from the foregoing that the

die support and operating members 15 and 16 are given a distinct movement toward and from each other, as will be apparent from a consideration of Figs. 6 to 10 inclusive, and these movements will be suitably controlled in a casting machine of the general type and kind under consideration.

Some of the illustrations in the accompanying drawings are somewhat diagrammatic for sake of clarity. It will be apparent with different types and kinds of workpieces, the plate members 44-45, including the end plates 48 and 49 will be varied, particularly with respect to spacing of adjacent or opposed surfaces thereof.

Considering Fig. 3 of the drawing, it will appear that the plates 44 and 45 have large recesses 44' and 45' in which the heads 26 of the pins 25 pass to provide free travel of the heads in these recesses. The narrow plate 48 engages a part only of the head, as will clearly appear in said figure.

It will also be understood that in mentioning the rate of die operation in forming castings, this rate may vary, depending upon the type and kind of casting material employed, particularly in comparing metallic castings with respect to plastic castings as the rate of plastic castings is usually somewhat less than that of forming metallic castings.

Having fully described the invention what is claimed as new and desired to be secured is:

1. In machines for forming die cast heads on pin members, a magazine for supporting pin members in stacked relation one upon the other, means on the magazine for guiding the pin members to predetermined position at the lower discharge end of said magazine, means forming a vertical channel in spaced relation to and below said magazine, with a horizontal channel placing the discharge end of the magazine stack in communication with the upper end of said vertical channel, a pair of die operating members having a pair of dies supported therein, said die operating members being movable toward and from each other to move the dies to closed and opened positions, said dies collectively forming a cavity in predetermined alinement with one end of aligned pin members in said stack, one die operating member having a finger to pick-up the lowermost pin member of the stack in order to deliver the same through said horizontal channel to the upper end of said vertical channel during closing movement of said member, said member having below and in spaced relation to said finger a platform movable across the vertical channel to catch the pin member delivered to said vertical channel and support the same in horizontal alinement with the die cavity, with the dies in open position, the other die operating member having a platform spaced with respect to the platform of the first member and movable across said vertical channel when the platform of the first member clears the vertical channel to allow the pin member to drop from a die alining position to a trimming station, and trimming tools at the trimming station for trimming the casting on the pin member during closing movement of said dies.

2. In machines for forming die cast heads on pin members, a magazine for supporting pin members in stacked relation one upon the other, means on the magazine for guiding the pin members to predetermined position at the lower discharge end of said magazine, means forming

a vertical channel in spaced relation to and below said magazine, with a horizontal channel placing the discharge end of the magazine stack in communication with the upper end of said vertical channel, a pair of die operating members having a pair of dies supported therein, said die operating members being movable toward and from each other to move the dies to closed and opened positions, said dies collectively forming a cavity in predetermined alinement with one end of aligned pin members in said stack, one die operating member having a finger to pick-up the lowermost pin member of the stack in order to deliver the same through said horizontal channel to the upper end of said vertical channel during closing movement of said member, said member having below and in spaced relation to said finger a platform movable transversely of the vertical channel to catch the pin member delivered to said vertical channel and support the same in horizontal alinement with the die cavity, with the dies in open position, the other die operating member having a platform spaced with respect to the platform of the first member and movable transversely of said vertical channel when the platform of the first member clears the vertical channel to allow the pin member to drop from a die alining position to a trimming station, trimming tools at the trimming station for trimming the casting on the pin member during closing movement of said dies, and a spring actuated catch adapted to check accidental movement of the pin members in said horizontal channel.

3. In machines for forming die cast heads on pin members, a magazine for supporting pin members in stacked relation one upon the other, means on the magazine for guiding the pin members to predetermined position at the lower discharge end of said magazine, means forming a vertical channel in spaced relation and below said magazine, with a horizontal channel placing the discharge end of the magazine stack in communication with the upper end of said vertical channel, a pair of die operating members having a pair of dies supported therein, said die operating members being movable toward and from each other to move the dies to closed and opened positions, said dies collectively forming a cavity in predetermined alinement with one end of aligned pin members in said stack, one die operating member having a finger to pick-up the lowermost pin member of the stack to deliver the same through said horizontal channel to the upper end of said vertical channel upon closing movement of said member, said member having below and in spaced relation to said finger a platform movable transversely of the vertical channel to catch the pin delivered to said vertical channel and support the same in horizontal alinement with the die cavity, with the dies in open position, the other die operating member having a platform spaced with respect to the platform of the first member and movable transversely of said vertical channel when the platform of the first member clears the vertical channel to allow the pin member to drop from a die alining position to a trimming station, trimming tools at the trimming station for trimming the casting on the pin member upon closing movement of said dies, a spring actuated catch adapted to check accidental movement of the pin members in said horizontal channel, said horizontal channel being formed by spaced guide plates maintained in fixed position with respect

to said relatively movable die operating members, and the delivery finger of said first named die operating member supporting the pin members in the stack until the first named die operating member has moved into a fully opened position.

4. In machines for die casting bodies on pin members, means forming a pin delivery station, a casting station and a trimming station, means comprising a magazine for delivering pin members in horizontal position to the delivery station, a channel between the delivery and casting stations for passing the pins by gravity directly and without interruption into the casting station, means for transferring pin members one at a time from the delivery station to said channel, means for supporting the pin members at the casting station, means for casting a die cast body on a pin member supported at the casting station, means for supporting a pin member with a cast body thereon at the trimming station, and trimming tools at said trimming station for trimming the cast body.

5. In machines for die casting bodies on pin members, means forming a pin delivery station, a casting station and a trimming station, means comprising a magazine for delivering pin mem-

bers in horizontal position to the delivery station, means for yieldably restraining the pin members at the delivery station, a pair of dies forming when in closed position a cavity around a pin member supported at the casting station, means for injecting casting material into the cavity to form a cast body on that part of the pin member disposed in said cavity, means movable with, and secured to, said dies for moving the pin members one at a time from the delivery station to the casting and trimming stations and for supporting the pin members at said stations, and trimming tools at the trimming station for trimming the cast body on a pin member at said station.
